(57) CLAIM

The ornamental design for a combined food and beverage tray, as shown and described.

DESCRIPTION

FIG. 1 is a perspective view of a combined food and beverage tray, showing my new design;

FIG. 2 is a side view thereof;

FIG. 3 is a back view thereof;

FIG. 4 is a front view thereof;

FIG. 5 is a bottom view thereof;

FIG. 6 is a top view of the beverage insert layout thereof; and,

FIG. 7 is a top view of the tray insert layout thereof.

The broken lines in the drawings depict portions of the combined food and beverage tray and form no part of the claimed design.
